UNITED STATES PATENT OFFICE.

JACK CARL JANKUS, OF SCRANTON, PENNSYLVANIA, ASSIGNOR, BY MESNE ASSIGNMENTS, TO ICELESS AUTOMATIC REFRIGERATOR COMPANY, A CORPORATION OF DELAWARE.

TURNING PLUG.

Application filed December 22, 1922. Serial No. 608,395.

This invention is an improved means for preventing leakage of gases or other fluids along the stem of a turning plug, and the important features thereof relate to the sealing, seating, packing and cooling of the plug and its operating stem.

The invention may be used in connection with a wide variety of plugs for controlling or through which pass various fluids, but 10 it is particularly useful where there are wide fluctuations in temperature, and where it is very desirable to prevent leakage of a fluid such for instance as ammonia, to the atmosphere.

15 In the accompanying drawings I have illustrated certain embodiments of my invention, although it will of course be understood that various other embodiments might be designed within the scope of my invention as defined in the appended claim. In these drawings:

Fig. 1 is a central longitudinal section through a device embodying my invention, said section being taken on the line 1—1 of 25 Fig. 2.

Fig. 2 is a central longitudinal section in a plane at right angles to the plane of Fig. 1, said section being taken on the line 2—2 of Fig. 1,

30 Fig. 3 is a section on the line 3—3 of Fig. 2.

Figs. 4, 5 and 6 are central longitudinal sections of other forms, and

Fig. 7 is an end view of Fig. 6;

35 The form illustrated in Figs. 1 and 2 is designed particularly for use in connection with or as a part of such an apparatus as that illustrated in the Rumpler and Rennau application, Serial No. 566,367, filed June 6th, 1922 for refrigerating apparatus. There is employed a tank 10 adapted to serve alternately as the boiler or the absorber of a refrigerating machine. A tube 11 is so positioned and supported that its inner end 12 40 may be swung downwardly to a position below the liquid level or raised to a position above the liquid level. This tube 11 is connected to an ammonia pipe 13 and the tube is operated either automatically or manually, 45 so that when the tube 11 is raised and heat is applied to the tank 10, the gas driven off from the liquid may pass through the tube 11 and pipe 13 to the condenser. When the tube 11 is lowered to bring its end 12 below

the liquid 11 and the supply of heat to the 55 vessel is shut off, the gas may return through the pipe 13 and tube 11 and escape into and be absorbed by the liquid. Such operation forms no portion of my present invention, but my invention may be employed in connection with the means for oscillating the 60 tube 11 and establishing communication between it and the stationary pipe 13.

The tank is illustrated as being provided with a hollow tubular projection 14 constituting a casing for a turning plug 15 which supports and operates the tube 11. The plug is shown as including two sections 15^a and 15^b having conical, oppositely facing 65 portions engaging with conical seats 16 and 17. The tube 11 is rigidly secured to the plug member 15^b and the interior of the tube 11 is in open communication with a passage 18 in this plug section, which latter passage extends axially through the plug section 70 15^b and is in permanent open communication with the pipe 13. Thus in any position of the tube 11 there is a free and unobstructed communication through the plug 75 and between the tube 11 and pipe 13. The 80 casing 14 has a section 19 which may be welded to the body of the casing. Within this casing section 19 is a conical seat 17. The pipe 13 may also project into this casing section and be welded thereto. Thus, 85 gas-tight connections are established at this side of the casing 14.

The two plug sections 15^a and 15^b are so connected that they have limited relative axial movement but are held against relative 90 rotation. The plug section 15^b is shown as fitting within a recess in the end of the plug section 15^a, and rigid with the tube 11, while the section 15^a has portions projecting axially beyond or into engagement with the tube 95 11, so as to lock the parts against rotation but permit free separation endwise. The plug section 15^a also carries a coil spring 20 which acts against the inner end of the plug section 15^b and tends to separate them 100 and hold both against their respective conical seats.

In axial alignment with the casing section 19 the casing 14 carries a second casing section 21 which is in the form of a 105 sleeve and encircles the stem 22 of the turning plug section 14^a. Within this sleeve is a shoulder 23 against which seats an an-

2

nular member 24 presenting the conical seat 16 for the plug section 15^a. The member 24 may be put in friction tight, or may be held against rotation by a suitable key-way, or may be threaded within the sleeve. The member 24 is comparatively short in respect to the length of the sleeve, so that beyond the outer end of the seat member there is an annular space within which is placed the valve stem packing. I do not wish to be limited to any specific form of packing, although preferably I employ an annular hollow tube elements 25 of comparatively soft metal. In any event the packing should be of such character that it is not affected by any ammonia gas which may leak past the conical seat 16 into contact with it, and will not be injuriously affected by temperature changes. The packing may be compressed by any suitable form of gland 26 having threaded or other engagement with the outer end of the sleeve 21. Encircling the sleeve is a second sleeve 27 cooperating with the inner one to form an annular water space having inlet and outlet connections 28 for water or other cooling fluid.

It will be noted that the turning plug projects from the body of the casing into the sleeve 21, and that the seat member 24 and the conical seat 16 are thus entirely encircled by the water jacket. The seat and the turning plug are thus kept comparatively cool, and at a fairly even temperature irrespective of wide fluctuations in the temperature of the liquid in the tank 10.

It will be further noted that any compression applied to the packing 25 to prevent leakage along the stem 22 does not in any way change or affect the tension of the spring 20 which acts to hold the plug against its seat. By making the plug section 15^a slightly larger than the plug section 15^b, and by making the seat member 24 removable, it is possible to weld the casting sections 19 and 21 to the body portion 14 of the casing prior to the grinding of the valve seats. After all of the welding has been done, the seat 17 may be ground by a suitable tool projected endwise through the sleeve 21 and the seat 16 may be ground before the seat member 24 is inserted. These advantages are important as the high temperature required for welding is liable to warp or distort the seats if these be so designed or constructed that it is necessary to grind them before the welding takes place.

The sleeve 21 is provided with a passage 29 therethrough from the water space to the packing space and the adjacent packing ring 60 may also have an aperture through it, and may have its side toward the stem open. Thus the water in the jacket may encircle the stem in direct contact with the latter and form a water seal so that in case any 65 ammonia should leak past the seat 16 and

past the packing, it will be absorbed by the water and carried off in the water circulating system.

The outer end of the stem 22 may be provided with any suitable means for oscillating the plug and raising and lowering the tube 11. It will be noted that the conical seats 16 and 17 are in axial alignment and oppositely disposed so that the spring 20 keeps the plug sections properly centered 75 and insures the proper swinging movement of the tube 11.

The casing 14 may have an outer end wall 30 within which is screwed a plug 31, the aperture through the wall 30 serving 80 as a filling opening after the apparatus has been completed and installed. This valve plug 31 may have a small passage through it closed by a needle valve 32 which may be opened to relieve excess pressure 85 or foul gases in the system, should such operation be necessary or desirable. The needle valve is normally concealed and protected, and leakage is additionally prevented by a cap 33.

In Fig. 4 I have illustrated my invention as applied to a form of turning plug used to control the flow of a liquid or gas. The plug 15^a is formed of a single piece, and is held against its seat by the coil spring 20^c 95 acting between the base of the turning plug and a closure section 19^c for the main casing 14^c. The casing is formed integral with the sleeve 21^c, while the valve seat member 24^c is on the opposite side of the shoulder 100 23^c from the valve stem packing. This valve seat member 24^c may be ground before inserting and may be rigidly secured in place in the casing in any suitable manner, as for instance by screw threads or key and key-way. Encircling the sleeve 21^c is the water jacket 27^c which latter communicates through a passage 29^c with a packing ring section which forms the water seal around the valve stem. The valve casing here illustrated has welded or otherwise rigidly secured thereto the pipes or pipe connections 105 35 and 36 for the fluid which is to be controlled by the valve plug, and the valve seat member 24^c has passages registering with 110 these pipes or pipe connections.

In Fig. 5 I have illustrated a construction very similar to that shown in Fig. 4, except that the seat 16^d for the turning plug is formed integral with the casing 14^d instead 120 of a separate seat member. This valve seat may be ground after installation and all welding or other heat treating operations are completed. After the insertion of the valve 15^d a closure plate 19^d may be inserted and soldered or otherwise secured to form a gas-tight joint. The packing and water seal construction may be substantially the same as that illustrated in Fig. 4. The valves shown in Figs. 4 and 5 may 135

be employed in the refrigerating system of the application above referred to for controlling the pipe leading to the bottom of the evaporator and through which liquids not readily volatile may be forced from the evaporator back to the boiler-absorber. Of course these valves are capable of various other uses.

5

In Figs. 6 and 7 I have shown my invention as applied to a further form of valve. The casing here shown is substantially the same as that shown in Fig. 5, except that it has a port which may connect through a pipe 40 to the lowermost part of the evaporator, a second port which may connect through a pipe 41 with the condenser of the refrigerating system, a third port which may connect through a pipe 42 with the bottom of the still, and a fourth port which may connect through a pipe 43 with the top of the still. The valve plug 15° has a passage 44 which may connect pipes 40 and 42, a passage 45 which may register with pipes 42 or 43, and a passage 46 communicating with passage 44 and registering with pipe 41 when passage 46 registers with either of the pipes 42 or 43. In normal operation the valve plug 15° is oscillated to connect pipe 41 of the condenser with either the bottom of the still through pipe 42 during the absorbing period, or the top of the still through pipe 43 during the heating or distilling period. When it is desired to remove accumulated liquid from the

10

15

20

25

30

bottom of the evaporator, the plug is turned 25 to connect the pipe 40 with the pipe 42 through the passage 44. The pipe 41 will now be closed and the gas pressure in the evaporator will force any liquid from the bottom up through the pipe 40 and back 40 to the still. The packing here shown is substantially the same as that above described. The water jacket may be omitted if desired.

Having thus described my invention, what I claim as new and desire to secure by Letters Patent is:

In combination, a turning plug presenting a conical portion, a stem for operating said plug, a casing including a sleeve encircling the stem and integral with the body of the 50 casing, said sleeve having a shoulder at its inner end, an annular member rigidly and detachably secured within said casing and abutting against said shoulder and presenting a conical seat for said plug, a packing 55 within said sleeve, means operating axially of the stem toward said annular member for compressing the packing, a spring acting axially on the plug in the opposite direction to hold it against said seat, and a water 60 jacket encircling said sleeve and communicating with the packing space within the sleeve said jacket having an inlet and an outlet for the circulation of water therethrough.

Signed at N. Y. city in the county of N. Y. and State of N. Y., this 16th day of Nov., A. D. 1922.

JACK CARL JANKUS.
